AUTOMATIC IGNITION CUT-OUT FOR
GAS ENGINES

Ralph D. Lacoé, San Diego, Calif.

Application October 17, 1934, Serial No. 748,767

11 Claims. (Cl. 290—38)

My invention relates to means for automatically cutting out the ignition for gas engines, and the objects of my invention are:

First, to provide an automatic ignition cutout for gas engines so that the ignition is automatically cutout as soon as the engine stops so that there is no drainage on the battery from the ignition when the engine is not in operation;

Second, to provide an apparatus of this class which operates automatically by vacuum release from the intake manifold of the gas engine;

Third, to provide an apparatus of this class which is controlled by a single operating push button from the dash of the automobile or other vehicle;

Fourth, to provide an apparatus of this class which is applicable for operation with the conventional starter and ignition system of automobiles and other vehicles;

Fifth, to provide an apparatus of this class which is not affected by backfire from the gas engine;

Sixth, to provide an apparatus of this class which is so constructed that it will operate effectively when the vacuum is low, for instance when operating under full throttle, and

Seventh, to provide an apparatus of this class which is very simple and economical of construction, easy to operate, efficient in its action, and which will not readily deteriorate or get out of order.

With these and other objects in view as may appear hereinafter, my invention consists of certain novel features of construction, combination and arrangement of parts and portions as will be hereinafter described in detail and particularly set forth in the appended claims, reference being had to the accompanying drawings and to the characters of reference thereon which form a part of this application, in which:

Figure 1 is a plan view of my apparatus shown in normal operating position in a fragmentary portion of a dashboard of an automobile; Fig. 2 is a sectional view through 2—2 of Fig. 1 showing some of the parts in elevation to facilitate the illustration; Fig. 3 is a transverse sectional view from the line 3—3 of Fig. 2; Fig. 4 is a partial sectional and elevational view of the apparatus shown in normal operating position, and Fig. 5 is a diagrammatical view of my apparatus shown in connection with the ignition and starting mechanism of a vehicle.

Similar characters of reference refer to similar parts and portions throughout the several views of the drawings.

The cylinder 1, cylinder head 2, plunger 3, plunger rod 4, plunger spring 5, plug 6, ball valve 7, tube 8, switch control 9, switch control plunger 10, switch control latch 11, switch control latch 12, ignition switch member 13, starter switch member 14, magnetic relay 15, relay switch 16, ignition distributor 17, spark plug 18, and starter motor 19, constitute the principal parts and portions of my automatic ignition cutout apparatus for gas engines.

The cylinder 1 is a hollow cylindrical member finished on its interior surface for the plunger 3 to reciprocate therein. It is provided with an extended reduced portion 1a in axial alinement therewith which is provided with a recess portion 1b adapted for supporting the spring 5 therein, shown best in Figs. 1 and 2 of the drawings. Said spring is supported at one end against the shoulders 1c forming the one end of the recess 1b. The portion 1a is provided with a reduced recess portion 1d communicating with the recess portion 1b and with another enlarged recess portion 1e which extends outwardly to the end thereof and is provided with a screwthread therein adapted to receive the plug 6 for stopping the end thereof, as shown best in Figs. 1 and 2 of the drawings. This plug 6, however, is provided with a small orifice 6a which is adapted to permit air to enter for releasing the vacuum and permitting the spring 5 to press the plunger inwardly in the cylinder 1, as shown in Fig. 1 of the drawings. Communicating with the recess 1e is an orifice 1f which communicates with an enlarged recess 1g which is screwthreaded at its outer side adapted to receive the end of the tube 8 which tube extends to and connects with the intake manifold of the gas engine to provide a vacuum connection with the cylinder 1. Mounted in this recess 1g is a ball valve 7 which is raised by the vacuum pressure but is adapted to prevent backfire effecting the operation of the plunger.

The plunger 3 consists of disk members 3a and 3b and leather 3c turned over at its periphery in the usual manner for engagement with the inner surface of the cylinder 1, as shown best in Figs. 1 and 2 of the drawings. Connected with the plunger 3 is a plunger rod 4 which serves as a guide for the spring 5, the one end of said spring 5 resting against a collar 4a in the member 4.

The spring 5 is a compression spring which tends to hold the plunger 3 inwardly in the cylinder, as shown best in Fig. 1 of the drawings. This plunger 3 is provided with an axially extending hub portion 3d which is adapted to engage a

latch member 11 with the inward movement of the plunger caused by the action of spring 5.

Mounted in the open end of the cylinder 1 is a cylinder head 2 which is secured therein. This cylinder head is provided in its normally operating upper side with a pin 11a upon which are pivotally mounted the bifurcated portions 11b and 11c of the latch member 11. This head is also provided with an extending lug 2a which serves as a stop for the downward movement of the latch 11, shown best in Figs. 2 and 4 of the drawings.

This head member 2 is also provided with an axially extending neck portion 2b which is provided with a reduced threaded portion 2c leaving shoulders 2d for one side of the dash D to rest against and the threads 2c are adapted to receive a nut 2e for clamping against the opposite side of the dash D for holding the apparatus in position on the dash of the vehicle.

20 The neck portion 2b is provided with a central bore 2f in which is reciprocally mounted the plunger member 10 which is provided with a push button head 10a thereon with a stop shoulder 10b to limit the inward movement of the plunger 10. 25 This plunger 10 is provided with a groove 10c which is adapted to receive the inner end of the spring latch 12 which is provided with a recess for holding the spring 12a, the one end of which rests against the pin 11a thus tending to hold the 30 latch 12 inwardly and when the plunger 10 is moved outwardly to certain position the latch 12 engages the groove 10c and holds the plunger from longitudinal movement. Upon sufficient pressure on the button 10a the latch 12 is moved 35 out of the groove 10c. Secured on the end of the plunger 10 is the switch control 9 which consists of an insulated disk member 9a which is adapted to engage the extending ends of the switches 13 and 14 with the shifting of the plunger 10. This control member 9 is provided in its 40 end with a groove 9b, shown best in Fig. 3 of the drawings, which is adapted to receive the pointed hook portion 11d of the latch member 11 so that said hook portion 11d is retained in the groove 45 9b when in the position shown in Fig. 4 of the drawings. The extended end of the member 9 is adapted to engage the extended end of the member 3d when the plunger 10 is pressed inwardly, as shown in Fig. 2 of the drawings, or when the 50 plunger 3 is pressed inwardly, as shown in Fig. 1 of the drawings.

The cylinder 1 is provided with a laterally extending support member 1h on which is supported an electrical contact 14a which is adapted to 55 contact with a contact 14b on the switch member 14 when the switch member 14 is shifted by engagement with the member 9a. Supported on the member 1h is a contact 13a which is adapted to be engaged by a contact 13b on the 60 switch member 13 when released by movement of the member 9a.

The switch member 13 is electrically connected with the ignition coil and distributor 17 through conductor 17a. The contact 13a connects with a 65 source of electrical energy at one side of the magnetic relay 15 and switch 16 through conductor 16a. The switch 14 is electrically connected with one side of the relay 15 by means of conductor 14c. The relay 15 connects with the starting motor of the vehicle through the switch 16 and conductor 19a. The switch 16 is held out of engagement with the relay 15 by means of a spring 16a. It will be here noted that the relay, ignition coil, distributor, starter motor, are all of conventional 75 type of vehicle ignition starting mechanism.

The operation is as follows: When it is desired to start the engine the plunger member 10 is pressed inwardly to the position shown in Fig. 2 of the drawings which causes the member 9a to engage the end of the switch member 14 causing contact between the members 14a and 14b, magnetizing the relay 15, operating the switch 16, and operating the starting motor 19. As soon as the motor is started the vacuum from the intake manifold holds the plunger 3 inwardly, as shown in Fig. 2 of the drawings, and the switch member 14 being a spring member moves the member 9a together with the plunger 10 outwardly until the member 9 is engaged by the latch member 11, as shown best in Fig. 4 of the drawings, and held thereby and as long as the engine continues to run, either idling or otherwise, the position of the plunger member 10 is as shown in Fig. 4 of the drawings. However, if the engine stops for any reason, the plunger member 3 is moved by the spring 5 to the position shown in Fig. 1 of the drawings which opens the contacts 13a and 13b by engagement by the switch member 13 and the ignition switch is then closed off. The engine may be stopped by taking hold of the button 10a and drawing it outwardly to the position shown in Fig. 1 of the drawings, whereupon the latch member 12 engages the groove 10c and holds the member 9a in position for holding the ignition switch open. It will be noted that the latch member 11 engaging the groove 9b in the switch control member 9 will prevent the plunger 10 from being pressed inwardly and operating the starter motor.

Though I have shown and described a particular construction, combination and arrangement of parts and portions, I do not wish to be limited to this particular construction, combination and arrangement, but desire to include in the scope of my invention, the construction, combination and arrangement substantially as set forth in the appended claims.

Having thus described my invention, what I claim as new and desire to secure by Letters Patent is:

1. In an automatic ignition cutout apparatus for gas engines, a cylinder, a plunger reciprocally mounted therein, a vacuum pressure means connecting with one side of a plunger in said cylinder, a spring tending to hold said plunger against said vacuum pressure, a switch control means operable by said plunger, and ignition and starter switch means in controlled relation with said control for opening the ignition switch upon release of the vacuum from the engine. 55

2. In an automatic ignition cutout apparatus for gas engines, a cylinder, a plunger reciprocally mounted therein, a vacuum pressure means connecting with one side of a plunger in said cylinder, a spring tending to hold said plunger against said vacuum pressure, a switch control means operable by said plunger, ignition and starter switch means in controlled relation with said control for opening the ignition switch upon release of the vacuum from the engine, and 60 plunger means for manually operating said plunger in the direction of the vacuum operation. 65

3. In an automatic ignition cutout apparatus for gas engines, a cylinder, a plunger reciprocally mounted therein, a vacuum pressure means connecting with one side of a plunger in said cylinder, a spring tending to hold said plunger against said vacuum pressure, a switch control means operable by said plunger, ignition and 70 75

starter switch means in controlled relation with said control for opening the ignition switch upon release of the vacuum from the engine, plunger means for manually operating said plunger in the direction of the vacuum operation, and latch means for supporting said switch control in varying positions.

4. In an automatic ignition cutout apparatus for gas engines, a vacuum pressure actuated plunger, means tending to actuate said plunger in opposition to the vacuum pressure, switch control means actuated by said plunger, an ignition switch of a gas engine engageable by said switch control means for opening said ignition switch, and plunger means for manually operating said switch control means.

5. In an automatic ignition cutout apparatus for gas engines, a vacuum pressure actuated plunger, means tending to actuate said plunger in opposition to the vacuum pressure, switch control means actuated by said plunger, an ignition switch of a gas engine engageable by said switch control means for opening said ignition switch, means in connection with the vacuum means for preventing back pressure in connection with said vacuum plunger and plunger means for manually operating said switch control means.

6. In an automatic ignition cutout apparatus for gas engines, a vacuum pressure actuated plunger means tending to actuate said plunger in opposition to the vacuum pressure, switch control means actuated by said plunger, an ignition switch of a gas engine engageable by said switch control means for opening said ignition switch, plunger means for manually operating said switch control means, and latch means for holding said switch control means in certain relative position to the ignition.

7. In an automatic ignition cutout apparatus for gas engines in which there is a conventional ignition system with switches and a conventional starting mechanism with switches, the combination with the ignition switches and starting mechanism with a pressure actuated plunger, means for actuating said plunger in opposition to said pressure actuated means, switch control means in operative relation with said plunger arranged to open the ignition switch when in one position and close the starting switch when in opposed position.

8. In an automatic ignition cutout apparatus for gas engines in which there is a conventional ignition system with switches and a conventional starting mechanism with switches, the combina-

tion with the ignition switches and starting mechanism switches of a pressure actuated plunger, means for actuating said plunger in opposition to said pressure actuated means, switch control means in operative relation with said plunger arranged to open the ignition switch when in one position and close the starting switch when in opposed position, manually operated means for operating said switch control means.

9. In an automatic ignition cutout apparatus for gas engines in which there is a conventional ignition system with switches and a conventional starting mechanism with switches, the combination with the ignition switches and starting mechanism switches of a pressure actuated plunger, means for actuating said plunger in opposition to said pressure actuated means, switch control means in operative relation with said plunger arranged to open the ignition switch when in one position and close the starting switch when in opposed position, manually operated means for operating said switch control means, and latch means tending to hold said manually operated means in certain position relative to said ignition and starting switches.

10. In an automatic ignition cutout apparatus for gas engines in which there is a conventional ignition system with switches and a conventional starting mechanism with switches, the combination with the ignition switches and starting mechanism switches of a pressure actuated plunger means for actuating said plunger in opposition to said pressure actuated means, switch control means in operative relation with said plunger arranged to open the ignition switch when in one position and close the starting switch when in opposed position, manually operated means for operating said switch control means, latch means tending to hold said manually operated means in certain position relative to said ignition and starting switches, said manually operated means adapted to open the ignition switch when in one position and close the starting switch when in opposed position.

11. In an automatic ignition cutout apparatus for gas engines, a pressure actuated plunger, means tending to actuate said plunger in opposition to the pressure, switch control means actuated by said plunger, an ignition switch of a gas engine engageable by said switch control means for opening said ignition switch, and plunger means for manually operating said switch control means.

RALPH D. LACOE. 55
